UNITED STATES PATENT OFFICE

MARSELIUS T. ASHE, OF GARDEN CITY, NEW YORK

VENDING MACHINE

Application filed December 30, 1927, Serial No. 243,708. Renewed February 14, 1931.

This invention relates to vending machines and has for its object to provide a new and improved device of this description.

The invention has a further object to provide a vending machine for vending materials such as gum, candy and the like and which is operated by means of a coin. The invention has further objects which are more particularly pointed out in the accompanying 10 description.

Referring now to the drawings, Fig. 1 is a front view of one form of vending machine embodying the invention.

Fig. 2 is a side view of the vending machine 15 shown in Fig. 1.

Fig. 3 is a sectional view taken on line 3—3 of Fig. 1.

Fig. 4 is a vertical, sectional view through the machine, with parts broken away.

20 Fig. 5 is an enlarged view of Fig. 4, with parts omitted.

Fig. 6 is an enlarged front view of the device shown in Fig. 4, with parts omitted.

25 Fig. 7 is an enlarged sectional view taken on line 7—7 of Fig. 4.

Fig. 8 is an enlarged sectional view taken on line 8—8 of Fig. 6, showing the coin returning mechanism.

Fig. 9 is an enlarged sectional view taken 30 on line 9—9 of Fig. 6.

Fig. 10 is a view of the locking bar on the back plate.

Like numerals refer to like parts throughout the several figures.

35 Referring now to the drawings, I have shown a vending machine having a case 1 provided with an enlargement 2 at the bottom thereof. The case is provided at the front with a mirror 3. The case contains 40 material to be vended and the vending mechanism.

I have shown a case containing two sets of vending mechanism placed side by side. These two mechanisms are similar and I will 45 describe one of them and apply the same reference numerals to the other with the addition of the exponent "a" to such reference numerals.

The coins, by means of which the device 50 is operated, are placed in the coin openings 4

and 4a. When the coin is placed in the coin opening 4, for example, (see Fig. 9), it passes into the coin chute 5. If a magnetic slug, instead of a coin, is inserted, it is removed from the coin chute by the magnet 13a.

If the material has been exhausted or substantially exhausted from the material receptacle 6, the coin will be returned to the purchaser. Under these conditions, the finger 7 which is connected with the shaft 8, 55 carried by the supports 8a, and which normally engages the material in the receptacle 6 exposed through the opening 9, is forced through said opening, when the material is exposed, by the weight 10, also connected with the shaft 8. This moves a coin stop 11 into the path of the coin in the chute and holds said coin. The movement of the coin stop which is pivotally connected to a fixed part 12 by the pivot 13, is brought about by 60 the finger 7 through the connecting piece 14 connected with the finger 7. The coin is returned to the purchaser from the coin stop 11 as hereinafter set out.

If there is material in the material receptacle 6, the coin stop 11 is out of the chute and the coin placed in the opening 4, drops through the chute into the coin holder 15 of the coin wheel 16 mounted upon the shaft 17. There are a plurality of coin holders 15 65 on the coin wheel. When the coins enter the coin holders 15, they are stopped by the projections 18, (see Fig. 6), which hold the coins so that a portion thereof projects beyond the coin holder, as shown in Figs. 6 and 9. This coin then connects the operating handle 19 with the material delivery member by means of the following mechanism. The operating handle, in this case, rotates and is provided 70 with a cam 19a. A cam engaging part 20, preferably a roller, engages this cam and is connected with an arm 21 pivoted at 22, (see Fig. 6) to the lower part of the machine.

The arm 22 is operatively connected to a 75 coin engaging part 23, (see Figs. 6 and 9). This connection is made by means of a connecting piece 24 which works in a slot 25 in the arm. This connecting piece is connected with the coin engaging part 23. The coin engaging part is rotatably mounted on the 80 85 90 95 100

shaft 17 by the side pieces 27, the connecting piece 24 being connected with one of these side pieces. The connecting piece 24 is connected to one of the side pieces 27a of the other coin engaging part 20a. The coin engaging parts 23, as above set out, are rotatably connected with the shaft 17 while the coin wheel is fastened to said shaft. The coin engaging device may be moved without rotating the shaft when there is no coin in the coin holder. When there is a coin in the coin holder so that the coin wheel is rotated, the shaft 17 is rotated.

Connected with the coin engaging part 23 is a coin returning member 28. Connected with the operating handle 18 is a rod 29 carrying a retracting spring 30 which has one end held by a stop 31, the other end engaging the upper end 32 of the arm 21. When the operating handle is rotated, the cam 19 engages the cam engaging part 20 on the arm 21 and causes the arm to be moved to the position shown in Fig. 8. If there is a coin in the coin holder, below the coin chute, this movement of the arm causes the coin engaging part 23 to engage the coin and move the coin wheel 16, giving it a partial rotation. This coin wheel when moved through a partial rotation, causes a partial rotation of the shaft 17. This shaft has connected therewith a pinion 33 which is operatively connected with a pinion 34 by means of an intermediate pinion 35. The shaft 36 of the pinion 34 carries the material delivering member 37. This member is provided with a series of supporting faces 38 which pass below the material receptacle 6, the lower piece of material therein being supported on one of these faces, (see Figs. 5 and 9). Opposite each face is a material engaging part 39.

When the material delivering member is moved forward one step, this material engaging part engages the lower piece of material in the receptacle and moves it from the receptacle discharging it into the material delivery chute 40, (see Figs. 4 and 9), where it may be removed by the purchaser through the opening 41. Another one of the supporting faces of the material delivering member passes under the material receptacle and receives the next piece of material. The pinions, shafts and associated parts are mounted upon suitable frame members 42 connected with the supports 43 by the fastening device 44. The cam 19 is arranged so that when the material delivering member has been moved forward a sufficient amount, that is, one step, the cam engaging part 20 and the arm 21 are returned to their initial positions by the spring 30. The movement of the operating handle 18 in either direction moves the cam engaging part 20 and the arm 21 forward due to the fact that the cam has two similar cam faces one on each side of the central line thereof. Some means

is provided for preventing the material delivering member from being moved too far and for insuring its being moved only one step at a time so as to discharge only one piece of material for each coin.

In the construction shown, this result is secured by mounting upon the shaft 17 a star wheel 45 having on its periphery a series of recesses 46. Co-operating with this star wheel is a wheel 47 which engages one of these recesses as shown in Fig. 5, when the material delivering member is in the proper position under the material receptacle 6. In order to maintain the star wheel and the wheel 47 in proper relation, the star wheel is provided on each side with the plates 48. This is very clearly shown at the left side of Fig. 6. The wheel 47 is movable with relation to the star wheel so that when the star wheel is rotated, it may move out of the recess and pass into the next recess.

In the construction shown, the wheel 47 is mounted upon the arm 49 pivoted to the frame 42 at 50. A retracting spring is provided to normally press the wheel 47 toward the star wheel 45. In the construction shown, this spring 51 is connected to an arm 52 connected with the arm 49 so that the two arms will move together. As the coin wheel 16 is rotated, the coins in the coin holders drop out as they pass below the shaft 17 and fall into the coin receptacle 53 and may be removed when the vending machine is refilled with material. If there is no coin in the coin holder of the coin wheel directly below the coin chute, the movement of the handle and the cam engaging part 20 and arm 21 will produce no effect, the coin engaging parts 23 and 23a simply rotating on the shaft 17 without moving the coin wheel 16. When the material has been exhausted, the coin stop 11 projects into the coin chute, as shown in Fig. 9. If, now, the handle is turned, the cam engaging part 20 and arm 21 move forward, but since there is no coin in the coin wheel, there is no movement of such coin wheel. During this forward movement of the cam engaging part 20, the end of the arm 54 engages the part 54 thereon engages the part 53 connected with the side 55 of the coin chute, (see Figs. 8 and 9), and moves the side 55 of the coin chute about a pivot so as to release the coin held by the coin stop 11. This coin then falls on to the coin return device 28 and is discharged into the return coin chute 57 which connects with the material delivering chute 40 so that the coin may be returned to the purchaser and be removed by him through the opening 41. The side 55 of the coin chute is moved back by the spring 58.

The part 59 of the coin chute is mounted upon a pin 60 provided with the torsional spring 61 which tends to hold it against the end of the side 62 of the coin chute. The

end of the coin chute is arranged to properly guide the coin into one of the coin holders 15 on the coin wheel 16. The parts are further arranged so that any device larger in diameter than the proper coin will not pass into the coin holder and hence cannot be used to secure the material vended. The back plate 63 of the casing is removable for replenishing the material in the material receptacles and for removing the coins. It is locked in position by means of a locking bar 64 hinged at 65, (see Figs. 10 and 11). A lock 66 is provided in the bottom of the casing for a key by means of which the locking bar may be released or held in its locking position.

It will be noted that by means of the projections 18 the coin wheel acts to calibrate the coins and when a coin is smaller than that for which the machine is adapted this coin will fall through and not operate the device.

I claim:—

1. A vending machine comprising a casing, a coin chute, a coin wheel under said chute, said coin wheel provided with a coin holder into which a part of the coin is received, the other part of said coin projecting therefrom, a coin engaging device for engaging the projecting part of the coin in said coin holder, an operating handle rotatable about its central axis and accessible on the exterior of the casing, a cam connected with said handle, and means actuated by said cam for moving said engaging part so as to move the coin wheel, a material delivering member adapted to deliver the material to be vended and an operative connection between said coin wheel and said material delivering member and means for preventing action of the device by something other than the coin for which the device is adapted.

2. A vending machine comprising a casing, a coin chute one side of which consists of a pivoted spring pressed member, a coin wheel under said chute, said coin wheel provided with a coin holder into which a part of the coin is received, the other part of said coin projecting therefrom, a coin engaging device for engaging the projecting part of the coin in said coin holder, an operating handle rotatable about its central axis and accessible on the exterior of the casing, a cam connected with said handle, and means actuated by said cam for moving said coin engaging part so as to move the coin wheel, a material delivering member adapted to deliver the material to be vended, and an operative connection between said coin wheel and said material delivering member, said material delivering member provided with a series of faces adapted to be successively brought in position to receive the material to be discharged.

3. A vending machine comprising a casing, a coin chute, a coin wheel under said chute,

said coin wheel provided with a coin holder into which a part of the coin is received, the other part of said coin projecting therefrom, said coin wheel being provided with means for preventing coins smaller than the coin for which the machine is adapted from operating the device, a coin engaging device for engaging the projecting part of the coin in said coin holder, an operating handle rotatable about its central axis and accessible on the exterior of the casing, a cam connected with said handle, and means actuated by said cam for moving said coin engaging part so as to move the coin wheel, a material delivering member adapted to deliver the material to be vended, an operative connection between said coin wheel and said material delivering member, and a coin stop for preventing the coin from entering the coin holder when the material to be vended has been exhausted.

4. A vending machine comprising a casing, a coin chute, a coin wheel under said chute, said coin wheel consisting of two separate members separated by a space and provided with a coin holder into which a part of the coin is received, the other part of said coin projecting therefrom, a coin engaging device for engaging the projecting part of the coin in said coin holder, an operating handle rotatable about its central axis and accessible on the exterior of the casing, a cam connected with said handle, and means actuated by said cam for moving said coin engaging part so as to move the coin wheel, a material delivering member adapted to deliver the material to be vended, an operative connection between said coin wheel and said material delivering member, a coin stop for preventing the coin from entering the coin holder when the material to be vended has been exhausted, and means for returning said coin to the purchaser.

5. A vending machine comprising a casing, a coin chute, a coin wheel under said chute, said coin wheel provided with a coin holder into which a part of the coin is received, the other part of said coin projecting therefrom, a coin engaging device for engaging the projecting part of the coin in said coin holder, an operating handle rotatable about its central axis and accessible on the exterior of the casing, a cam connected with said handle, and means actuated by said cam for moving said coin engaging part so as to move the coin wheel, a material delivering member adapted to deliver the material to be vended an operative connection between said coin wheel and said material delivering member, and means for preventing a device different in diameter from the coin for which the machine is adapted, from lodging in said coin holder.

6. A vending machine comprising a coin chute, a material receptacle the material receptacle and chute being side by side a coin stop normally out of the way of the coin,

means for automatically moving the coin stop in to the path of the coin to stop said coin when the material to be vended is exhausted, and means for releasing said coin when the machine is operated and returning it to the purchaser.

7. A vending machine comprising a coin chute, a coin stop normally out of the way of the coin, means for automatically moving the coin stop in to the path of the coin to stop said coin when the material to be vended is exhausted, a coin wheel below said coin chute, a coin holder on said wheel, a coin engaging part and means connected with said coin engaging part for releasing the coin from said coin stop.

8. A vending machine comprising a coin chute, a coin stop normally out of the way of the coin, means for automatically moving the coin stop into the path of the coin to stop said coin when the material to be vended is exhausted, a coin wheel below said coin chute, a coin holder on said wheel, a coin engaging part, means connected with said coin engaging part for releasing the coin from said coin stop, and a coin returning device connected with said coin engaging part for directing the coin so that it will be returned to the purchaser.

80 Signed at Chicago, county of Cook, and State of Illinois, this 15th day of December, 1927.

MARSELIUS T. ASHE.
